UNITED STATES PATENT OFFICE.

MARTYN ARNOLDUS VAN DER WIELEN, OF ROTTERDAM, NETHERLANDS.

COIN-CONTROLLED LIQUID-VENDING APPARATUS.

SPECIFICATION forming part of Letters Patent No. 763,645, dated June 28, 1904.

Application filed December 7, 1903. Serial No. 184,171. (No model.)

To all whom it may concern:

Be it known that I, MARTYN ARNOLDUS VAN DER WIELEN, director, a citizen of the Netherlands, residing at Rotterdam, in the Netherlands, have invented new and useful Improvements in Coin-Controlled Liquid-Vending Apparatus, of which the following is a specification.

My invention relates to a coin-controlled apparatus for delivering certain quantities of liquid—for instance, water—in proportion to the one or several coins inserted. The new apparatus is preferably arranged in connection with a liquid-meter, and essentially comprises a valve-box with two valves, (the one for receiving liquid from the liquid-meter and the other for discharging the liquid measured,) two levers for actuating the two valves, a locking-wheel, gearing connecting the liquid-meter with the locking-wheel for driving the latter, an arm for disengaging the locking-wheel from the gearing, a detent for locking or releasing the locking-wheel, and a hand-slide arranged to move, by means of the coin inserted, the two valve-actuating levers severally and the disengaging locking-wheel through a corresponding angle, whereupon this wheel is again engaged. The whole construction of the new liquid-vending apparatus will be hereinafter more particularly described, with reference to the accompanying drawings, in which—

Figure 1 is an elevation of the apparatus in a form of construction, the normal position of the hand-slide being indicated by dotted lines. Fig. 2 is a plan of the same. Fig. 3 is a vertical longitudinal section through the apparatus without liquid-meter and registering device on the line A A in Fig. 2, the hand-slide occupying its normal position. Fig. 4 is a horizontal section through the same on the line B B in Fig. 1. Fig. 5 is a vertical cross-section through the valve-box on the line C C in Fig. 4. Fig. 6 is a vertical section similar to Fig. 3 in which the hand-slide has been pushed inward a little. Fig. 7 is a horizontal section through the valve-box, the two valves being closed by the parts shown at Fig. 6. Fig. 8 is a vertical section similar to Fig. 3 in which the hand-slide is pushed inward

through a farther distance. Fig. 9 is a similar vertical section in which the hand-slide is farther pushed inward and so much that the locking-wheel is disengaged from its gearing. Fig. 10 is a horizontal section similar to Fig. 4 in which the parts occupy the same positions as in Fig. 9. Fig. 11 is a vertical section similar to Fig. 3 in which the hand-slide occupies its extreme positions when pushed inward; and Fig. 12 is a horizontal section similar to Fig. 4, showing the relative positions of the parts for the same extreme position of the hand-slide as before.

Similar numerals indicate similar parts throughout the several views.

The coin-controlled apparatus is mounted on the base 1, of sheet metal, and is in connection with a known liquid-meter (or water-meter) 2. The construction of the liquid-meter 2 is immaterial, it being only essential that the liquid-meter 2 be provided with a projecting shaft 14, (see Fig. 3,) which is driven in any known manner by the liquid passing through the meter while being measured. The liquid is assumed to enter the meter 2 through the inlet 42 and to leave the same through the outlet 43. To the casing of the liquid-meter 2 a conveniently-shaped frame 4 is secured, which may be supported by a leg 3 shown. The driving-shaft 14 is tightened by a suitable stuffing-box 44 and is arranged to drive a vertical shaft 16 within the frame 4 by means of the bevel-wheels 15 and 17. The shaft 16 actuates a registering device 18 of any known construction, so that the quantity of the liquid passed through the meter 2 will be shown on the dial of the said device. On the lower end of the shaft 16 a pinion 19 is fastened, which engages a gear-wheel 20, secured on a vertical shaft 45. The latter is mounted to turn in a special frame 46, fastened on the bottom part of the frame 4. Secured to the shaft 45 is a second gear-wheel 21, which can engage with a gear-wheel 22, secured on a vertical shaft 23. On the frame 46 is fastened a guide 26 for the hand-slide 27. The guide 26 has a vertical front wall to which the vertical coin-channel 28 is attached.

The whole apparatus may be assumed to be

so inclosed in a suitable casing (not shown) that the upper end of the coin-channel 28 terminates in the top face of the casing and that the knob 48 of the hand-slide 58 27 always 5 remains without the casing, while the inlet 42 of the liquid-meter 2 and the outlet 53 (which will be referred to later on) just project through suitable holes in the casing.

The guide 26 is provided with a boss 49, in 10 which the shaft 23 turns. On this shaft 23 a locking-wheel 24 is fastened, which will be described later on. On the upper end of the shaft 23, between the top part of the frame 4 and a bearing 47, secured thereto, a gear- 15 wheel 37 is arranged so that it is prevented from moving vertically, while the shaft 23 can be shifted longitudinally. It will be evident that on raising the shaft 23 in a manner to be described hereinafter the gear-wheel 22 will be disengaged from the gear-wheel 21, (see Fig. 9,) so that the locking-wheel 24 can be turned as desired.

A valve-box 5, Fig. 5, is secured on the top plate of the frame 46 and provided with two 20 horizontal externally-threaded tubes 6 and 7, (see Fig. 4,) which thus can be adjusted longitudinally and secured by means of counter-nuts 50 50. The one tube, 6, is connected with the outlet 43 of the liquid-meter 2 by means 25 of a tube 51 and a coupling 52. The other tube, 7, is cast in one piece with a nut 53, into which a discharging tube or piece (not shown) is to be screwed.

The two tubes 6 and 7 are placed in two different vertical planes parallel to each other, and their internal ends serve as seats for the two valves 8 and 9. A horizontal shaft 10 at right angles to the hand-slide 58 27 and the two tubes 6 and 7 is mounted to turn in the valve- 30 box 5 and the front wall of the guide 26. (See Fig. 4.) On this shaft 10 an arm 54 is fastened, to which the one valve, 8, is so hinged that it can readily apply itself to its seat on the shaft 10. On the front end of the shaft 45 10 a lever 30 of the shape shown at Fig. 3 is fastened, by which the valve 8 is controlled. A sleeve 13 loosely surrounds the shaft 10 and passes through the cover of the valve-box 5, in which it is tightened by means of a stuffing-box 11. The external end of the sleeve 13 is made thick and equally tightened by another stuffing-box, 55. On the sleeve 13 within the valve-box 5 an arm 56 is fastened, to which the other valve, 9, is hinged, as shown at Fig. 55 5, so that it applies itself to its seat on the sleeve 13. On the external thick end of the sleeve 13 is fastened a bent lever 31 of the shape best shown at Fig. 11 for controlling the valve 9. On the hub of this lever 31 a 60 detent 32 (see Fig. 11) is fastened, which is arranged for engaging in the deep cut 25 of the locking-wheel 24, and thereby locking the latter. The detent 32 is provided on the lower surface of its free end with a ball 36, which 65 is so held that it can freely roll on the top sur-

face of the locking-wheel 24 during the rotation of the latter, whereby the friction is reduced. On the detent 32 a bent arm 33 (see Fig. 9) is fastened, which is adapted to raise the locking-wheel 24, and thereby disengage it 70 from the gearing. A spiral spring 35 is attached at the one end to the top part of the frame 4 and at the other end to the detent 32. This spring serves for pressing the detent 32 on the locking-wheel 24, and on the former 75 engaging in the cut 25 the spring 35 also serves for pressing the valve 9 against its seat, and thus stopping the delivery of the liquid.

A fork-shaped slide 58 is mounted to move longitudinally in the guide 26 and is rigidly 80 connected with a rod 27 to form a hand-slide which can be pushed inward and drawn out by means of the knob 48. This slide 58 is so much cut out as to leave in its extreme position (shown at Fig. 11) sufficient space for 85 the two levers 30 and 31. Near the left end the slide 58 is provided in its two arms with two vertical cuts 59 59, in which the coin 29, Figs. 6 and 8, inserted is allowed to move vertically. When drawn out, the hand-slide occupies such an extreme position that its cuts 59 59 register with the opening in the coin-channel 28, (see Fig. 4,) so that the coin 29 inserted falls into these cuts 59 and is thereby held. The bottom of the guide 26 is provided 95 with three slots 60, 61, and 34. The one slot, 60, is so shaped as to allow the coin 29 to assume its lowest position (shown at Fig. 3) and to permit it to again rise on the hand-slide being pushed inward from right to left, Fig. 100 6. The second slot, 61, is necessary for leaving space to the two levers 30 and 31. The third slot, 34, registers with the cuts 59 when the hand-slide occupies its extreme position. (Shown at Fig. 11.) The slot 34 leads 105 to a channel 62, Fig. 1, through which the coin 29 can drop and fall into a convenient receptacle, (not shown,) guided by the two guides 63 63 on the base 1.

The locking-wheel 24 has several (here six) 110 teeth, against either of which the coin inserted is adapted to strike, so as to turn the locking-wheel through a corresponding angle. (See Fig. 10.) As the locking-wheel 24 is prevented from turning when the detent 37 engages in its cut 25, it will be evident that five coins at the utmost can be inserted one after the other and pushed against the locking-wheel 24 to turn it in the direction of the arrow. To prevent the locking-wheel 24 from 115 turning further, the gear-wheel 37 engages in a rack 38, provided with a pointer 39, which latter projects through a slot of the scale 40. It is evident that on the pointer 39 pointing at "5" of the scale 40 it will be stopped by the 120 end of the slot and cannot move farther. The scale 40 may also be made visible through a convenient opening or a glass plate in the casing inclosing the apparatus.

In order to enable the gear-wheel 22 to at 130

once engage in the teeth of the other gear-wheel, 21, on the locking-wheel 24 again dropping, the slide 58 is provided with a block 41, Fig. 10, which is cut off slantingly, so that it 5 bears against the back of either tooth of the locking-wheel, and thereby brings the latter into the correct position for dropping.

The apparatus described so far is operated as follows: Normally the hand-slide 58 27 occupies its extreme position when drawn out and the detent 32 engages in the cut 25 of the locking-wheel 24, so that the discharging-valve 9 is pressed on its seat by the spiral spring 35, and thereby stops the delivery. 15 (See Figs. 3 to 5.) On inserting a coin 29 in the channel 28 it will fall into the cuts 59 59 of the slide 58 and occupy the position shown at Fig. 3. On pushing inward the hand-slide by means of the knob 48 the coin 29 will soon 20 strike against the lower inclined surface of the lever 30 and raise the latter. At the same time the coin 29 is forced by the curved surface of the slot 60 to rise and to further turn upward the lever 30, so that the lower edge 25 of the latter is now horizontal. (See Fig. 6.) In consequence of this motion of the lever 30 with the shaft 10 the receiving-valve 8 is applied to its seat. At this moment the coin 29 strikes against the second lever 31 and raises 30 it, so as not only to detach the discharging-valve 9 from its seat, but also to first disengage the detent 32 from the locking-wheel 24 (see Fig. 8) and then to raise the latter by means of the arm 33 out of engagement with 35 the gearing. (See Fig. 9.) Now the coin 29 strikes against the respective tooth of the locking-wheel 24 and turns the latter in the direction of the arrow in Fig. 10 through the distance of a pitch, when the slide 58 will attain 40 its other extreme position and the coin 29 drops through the slot 34 and the channel 62 into the receptacle. Then the two levers 30 and 31 are released, so that the one, 30, returns into its initial position and opens the 45 receiving-valve 8, while the other lever, 31, is checked by the locking-wheel 24 dropping into engagement with the gearing, so that the discharging-valve 9 remains in its opened state. Under the pressure of the liquid the 50 meter 2 is now started, so that liquid passes therefrom through the tubes 51 and 6, the valve-box 5, and the tube 7 to the outlet. At the same time the driving-shaft 14 is rotated to turn back the locking-wheel 24 in the direction of the arrow in Fig. 12 and also to actuate the counter 18. Of course during this 55 time one or several further coins may be inserted to turn the locking-wheel 24 forward if the quantity of liquid vended is to be increased. In case five coins in all are inserted the locking-wheel 24 will be so turned that its cut 25 is brought into the position indicated by the dotted lines in Fig. 12. The liquid will continue flowing out until the locking- 60 wheel 24 returns into its initial position, when

the detent 32, under the action of the spiral spring 35, will fall into the cut 25 and stop the wheel 24. Thereby also the discharging-valve 9 is again closed.

It is evident that the quantity of the liquid 70 delivered depends upon the number of coins inserted, as the locking-wheel 24 will take the more time to return into its initial position the more coins are introduced.

The coin-controlled liquid-vending apparatus can be varied in many respects without deviating from the spirit of my invention. 75

What I claim as my invention, and desire to secure by Letters Patent, is—

1. In a coin-controlled liquid-vending apparatus, the combination with a source of liquid, of a valve-box, two valves in said valve-box, means for conducting liquid from said source of liquid to one of said two valves, an outlet for discharging the liquid, from the other of said two valves, a spindle mounted to turn in said valve-box and connected by an arm with the one of said two valves, a sleeve loosely surrounding said spindle and connected by an arm with the other of said two valves, two levers outside said valve-box of which the one is fastened on said spindle and the other on said sleeve, a locking-wheel, means actuated by the liquid conducted to one of said two valves for driving said locking-wheel, a detent 90 rigidly connected with one of said two levers and adapted to lock and release said locking-wheel, and a hand-slide adapted to receive the coin inserted and to strike it against said two levers severally and against a tooth of said locking-wheel until the coin drops and releases them. 95

2. In a coin-controlled liquid-vending apparatus, the combination with a source of liquid, of a liquid-meter connected with said source 105 of liquid, a valve-box connected with the outlet of said liquid-meter and provided with an outlet, two valves in said valve-box for controlling the liquid entering and the liquid discharged respectively, a spindle mounted to 110 turn in said valve-box and extending to the outside, an arm fastened on said spindle within said valve-box and adapted to open and close the one of said two valves, a sleeve loosely surrounding said spindle, an arm fastened on 115 said sleeve within said valve-box and adapted to open and close the other of said two valves, two levers without said valve-box of which the one is fastened on said spindle and the other on said sleeve, a locking-wheel provided 120 with a plurality of teeth and a cut, means actuated by said liquid-meter for driving said locking-wheel, a detent rigidly connected with one of said two levers and adapted to engage in the cut of said locking-wheel, an arm rigidly connected with said detent for disengaging from said means said locking-wheel when released and a hand-slide adapted to receive the coin inserted and to strike it against said 125 two levers severally and against either tooth 130

of said locking-wheel until the coin drops and releases them.

3. In a coin-controlled liquid-vending apparatus, the combination with a source of liquid, of a liquid-meter connected therewith, a valve-box connected with the outlet of said liquid-meter and provided with an outlet, two valves in said valve-box for controlling the liquid entering and the liquid discharged respectively, 10 a horizontal spindle mounted to turn in said valve-box and extending to the outside, an arm fastened on said spindle within said valve-box and adapted to open and close the one of said two valves, a sleeve loosely surrounding said spindle, an arm fastened on said sleeve within said valve-box and adapted to open and close the other of said two valves, two levers without said valve-box of which the one is fastened on said spindle and the other on said 15 sleeve, said two levers being adapted to open the one and to close the other of said two valves when turned upward and vice versa, a vertical shaft movable longitudinally and carrying a gear-wheel, gearing transmitting the rotation from said liquid-meter to said gear-wheel, a locking-wheel fastened on said vertical shaft and provided with a plurality of teeth and a cut, a detent rigidly connected with one of said two levers and adapted to normally engage 20 downward in the cut of said locking-wheel, a spring for pressing said detent downward and thereby closing the one valve controlling the liquid-delivery, an arm rigidly connected with said detent for raising said locking-wheel when released, and a horizontal hand-slide adapted to receive the coin vertically inserted and to thereby turn upward 25

said two levers severally and also to strike the coin against either tooth of said locking-wheel in its raised position for turning same forward through an angle in a direction opposite to that of said gear-wheel, until the coin drops. 30

4. In a coin-controlled liquid-vending apparatus of the kind described, the combination 45 with a source of liquid, of a liquid-meter connected therewith, means for controlling the passage of the liquid through said liquid-meter, a shaft movable longitudinally and carrying 50 a gear-wheel, gearing transmitting the rotation from said liquid-meter to said gear-wheel, a locking-wheel fastened on said shaft and provided with a plurality of teeth and a cut, a detent adapted to normally engage in the cut of said locking-wheel for so actuating 55 said means as to stop the liquid-delivery, an arm for moving said gear-wheel out of engagement with said gearing, a hand-slide adapted to receive the coin inserted and to thereby actuate said means and said arm also 60 to strike the coin against either tooth of said locking-wheel for turning the latter through an angle, a second gear-wheel mounted on said shaft, a rack engaging said second gear-wheel and carrying a pointer, and a visible 65 scale for said pointer.

In testimony whereof I have signed my name to this specification in the presence of two subscribing witnesses.

MARTYN ARNOLDUS VAN DER WIELEN.
